ENDLESS BUCKET CONVEYER DITCH
DIGGING MACHINE

Almus H. Gardner and Charles W. Pewthers,
Henderson, Tex., assignors to Longhorn Industries, Inc., Henderson, Tex., a corporation of Texas

Application August 31, 1948, Serial No. 46,994

2 Claims. (Cl. 37—90)

1

This invention relates to new and useful improvements in ditch digging machines.

One object of the invention is to provide an improved ditch digging machine which is relatively light in weight, small and compact in construction with a low overhead clearance, whereby said machine may be efficiently operated in close areas or spaces in which the usual larger and heavier machines, now in general use, cannot be employed.

An important object of the invention is to provide an improved ditch digging machine, wherein the digging boom is disposed in a forward and downward direction with respect to the forward movement of the machine so that the force created by the digging action of the machine is in a direction which urges or holds the rear end of the machine downwardly against the ground, thereby making it possible to construct the machine of extremely light weight, as compared to the heavy weight of this type of machine now in general use; the light weight of the machine also permitting pneumatic or rubber tires to be employed, whereby the machine may be operated under its own power over all roads and the necessity of hauling or transporting the same on a truck or vehicle is eliminated.

Another object of the invention is to provide a ditch digging machine of the character described, having an improved bucket assembly mounted on the digging boom, which assembly is so constructed that there is no packing of the dirt or mud and the digging elements of the buckets are, in effect, self-cleaning which facilitates more efficient digging.

A particular object of the invention is to provide an improved ditcher, of the character described, wherein the digging buckets are mounted on the digging boom in such manner that the centrifugal force developed by the buckets as they pass around the end of the boom is utilized to effectively discharge the contents thereof to empty said buckets; said digging buckets having forwardly disposed digging elements and outwardly flared side digging teeth or blades, the latter functioning to shave or remove the earth at the sides of the ditch being formed by the machine to assure efficient operation.

Still another object of the invention is to provide an improved ditch digging machine wherein the digging boom and bucket mounting is such that the digging buckets "tunnel under" or rip out the earth with the result that the actual digging causes a downward force to be constantly exerted on the machine to prevent lifting of said

2

machine, even though relatively light weight, under hard or difficult digging conditions.

A specific object of the invention is to provide an improved mobile ditcher, of the character described, wherein the rear wheels of the machine, are mounted to permit individual or independent adjustment of each wheel in a vertical plane, whereby the machine may be operated with the rear wheels on different offset horizontal planes or on inclined terrain while still digging a truly vertical ditch.

Other and further objects of this invention will appear from the following description.

In the accompanying drawings which form a part of the instant specification, are to be read in conjunction therewith, and wherein like reference numerals are employed to designate like parts in the various views:

Figure 1 is a side elevation of a ditch digging machine, constructed in accordance with the invention.

Figure 2 is a plan view, with certain parts removed to clearly illustrate the driving connections.

Figure 3 is a side elevation of the digging boom and bucket assembly.

Figure 4 is a bottom view of the assembly shown in Figure 3.

Figure 5 is a side elevation of the chute on the digging boom.

Figure 6 is an end elevation thereof.

Figure 7 is an isometric view of the mounting for one of the rear wheels.

Figure 8 is an enlarged side elevation of the digging and receiving buckets.

Figure 9 is a view taken from the underside of the parts shown in Figure 8, and

Figure 10 is a transverse sectional view of the dirt removing conveyor, taken on the line 10—10 of Figure 2.

In the drawings, the numeral 10 designates the main frame of the improved ditch digging machine and includes longitudinally extending base members 11 and upper angle members 12, which are connected in any suitable fashion by upright connecting angles or members 13. The members 11 and 12 on each side of the machine are connected with each other by transverse connecting channels or bars 14 and any desired number of the transverse connecting members may be provided to form a rigid frame structure. It is desirable that all of the various members be welded or otherwise secured together, and it is obvious that the particular details of construction of the frame are subject to variation.

The forward end of the frame is supported by a pair of relatively small front wheels 15, while the rear portion of the frame is supported by enlarged rear drive wheel 16. The rear wheels 16 are mounted for vertical adjustment and as is clearly shown in Figure 7, each wheel is mounted upon a stub axle 17, which extends outwardly from a supporting block 18. The supporting block 18 is mounted for sliding movement between upright supports 19, the vertical edge portions of said block being movable within vertical slots 20 formed in the upright 19. An adjusting screw 21 is threaded through a collar 22, which is welded or otherwise secured to the upper angle member 12 of the frame and the lower end of the screw 21 bears against an outwardly extending lug 23 which is secured to the supporting block 18. It is apparent that with each rear wheel 16 mounted upon its respective axle, the weight of the frame tends to move the block 18 upwardly within the upright 19, and the elongate adjusting screw 21 limits such upward movement. By rotating the screw 21 to move said screw upwardly, a further upward movement of the block 18 and its respective wheel 16 may be effected with respect to the frame 10. In this manner, the vertical disposition of the rear wheels 16 may be changed, whereby the machine may travel over inclined terrain or over an area where each rear wheel is disposed in a different horizontal plane.

Each rear wheel 16 has a driving sprocket 24 secured to its inner surface and an endless drive chain 25 passes over this sprocket as well as over a drive gear 26 which is mounted on a drive shaft 27 at the upper portion of the frame 10. The drive shaft 27 extends transversely across the frame (Figure 2) and has the drive gear 26 secured to its ends outside of the frame. The drive shaft 27 is driven through a suitable speed reduction gearing 28, drive chain 29, manually controlled transmission 30 and jack shaft 31 by the main drive shaft 32 of a suitable engine 33. The engine drive shaft has connection with the jack shaft through drive pulleys and belts 34, and a suitable variable speed transmission 35 may be connected in the jack shaft 31. Thus, when the transmission 30 is properly manipulated, a rotation is imparted to the drive gears 26 and through the chain 25 and sprocket 24, a rotation is transmitted to the rear wheels 16 of the machine. The drive chain 25 which surrounds the sprocket 24 and drive gear 26 of each wheel is provided with sufficient slack to permit the vertical adjustment of each wheel, and in order to maintain said chain taut during the driving connection, a suitable idler gear 36 which is maintained under constant tension by a spring 37 engages said chain (Figure 1).

A digging boom and bucket assembly A is mounted within the frame 10 and has its upper end suspended from a transversely extending shaft 38 which is mounted between the rear uprights 13 of said frame. The assembly A is adapted to be lowered into the position shown in Figure 1, in which position the lower portion of said assembly engages the earth, wherein the ditch is to be formed. In such position, the boom assembly is directed downwardly and forwardly within said frame. The assembly includes an endless chain B on which buckets C are mounted and said chain passes over sprockets 39, which, as will be described, are mounted at each end of assembly A. For imparting rotation to the upper sprocket 39 to transmit mo-

tion to the buckets C and C', the shaft 38 on which the upper sprocket is mounted extends outwardly to one side of the frame and has a drive gear 40 secured thereto (Figure 2). The gear 40 is rotated through a chain drive 41, gear box 42, and chain drive 43, the latter being connected or driven by a gear 44 mounted on the main drive shaft 32 of the engine. A suitable manually controlled transmission 45 is connected in the drive shaft 32, whereby a control of the movement of the buckets of the assembly A may be had.

Lowering and raising of the assembly A is controlled by a lifting cable 46 which has one end wound around a winch or drum 47, which is mounted in an upright support 48 secured to the top of the frame 10. An enlarged gear 49 is secured to the winch or drum shaft and is adapted to mesh with an operating pinion 50 which is controlled by a hand crank 51. The free end of the cable 46 passes over a roller secured to the assembly A and is then attached to one of the upper frame members 12; obviously, when the winch or drum 47 is actuated, the cable is wound upon or unwound from said drum with the result that the assembly A may be lowered or raised.

When the boom and bucket assembly A has been lowered into digging position as illustrated in Figure 1, its lower portion is directed forwardly and downwardly with respect to the forward movement of the machine. Upon forward movement of the machine and operation of the buckets C, earth is removed and carried upwardly by said buckets. This earth or dirt is discharged from the buckets by the centrifugal force which is developed as said buckets move over the upper sprocket 39. The discharged earth falls downwardly through a hood or enclosure 52, which is mounted on the rear end of the frame 10. Beneath the hood or enclosure is an endless conveyor 53 which extends transversely across the rear end of the machine. This conveyor is clearly shown in Figure 10 and comprises adjustable side plates 54 and 55 having a belt conveyor 56 disposed therebetween. The belt conveyor 56 passes around rollers 57 mounted on shafts 58 having their ends journaled in the adjustable side plates 54 and 55. The conveyor 56 functions to carry the dirt deposited thereon transversely of the rear end of the machine and to deposit said dirt at one side of the machine. If desired, a suitable shield 59 may be secured to the side plates 55 at the discharge end of the belt conveyor, whereby the dirt will be properly discharged in a single row as the machine moves forwardly.

For driving the belt conveyor 56, one of the shafts 58 is extended and has a drive sprocket 60 mounted thereon. An endless chain 61 connects the sprocket with a driving gear 62 which is mounted upon a jack shaft 63. The jack shaft is, in turn, driven by a suitable chain drive 64 which has connection with the main drive shaft 32 of the engine 33.

The particular disposition of the boom assembly A which, as has been pointed out, is forwardly and downwardly of the machine, causes the buckets to tunnel under or rip out the earth. Thus, the actual digging operation causes a downward force to be exerted on the rear portion of the machine, and the harder the digging, the greater is the pull on said machine to hold the rear wheels firmly in engagement with the ground. With this arrangement the entire unit may be made

relatively light in weight, as compared to the general type of machines of this character now in general use. As an example, the particular machine illustrated and described herein is capable of digging a ditch 8 to 12 inches in width with a maximum depth of 3½ feet, and the entire weight of such machine is approximately 5,000 pounds. Other machines now in general use for performing this digging operation weigh in the neighborhood of 10,000 to 15,000 pounds. The necessity for this increased weight is occasioned by the fact that the digging boom in the normal machine projects rearwardly and downwardly behind said machine, and the digging operation tends to lift the rear end of the machine, rather than to hold it down as is the case in the present machine.

The particular construction of the boom and bucket assembly A is illustrated in Figures 3-5, 8 and 9, and said assembly includes a fabricated boom which is constructed of side plates 65, a bottom plate 66 and a top plate 67, these plates being welded together to form a substantially square supporting element. Offset brackets 68 are secured to the upper portion of the boom and have bearing plates 69 fastened to their outer offset ends. The shaft 38 on which the upper sprocket 39 is mounted extends through the bearing plates 69 and obviously with this arrangement the boom is suspended for rotation from the shaft 38.

The lower sprocket 39 of the assembly A is mounted on a shaft 70 which has its ends supported within one extremity the elongated supporting bars 71. As is clearly shown in Figures 3 and 4, the bars 71 overlie the sides 65 of the boom and are connected thereto by bolts 72 which pass through elongate slots 73 in said bars and through openings 74 in the sides of said boom. Because of the slots 73, it is apparent that the bars 71 may be moved or adjusted longitudinally with respect to the boom and for effecting this adjustment, each bar 71 has an adjusting screw 75 associated therewith. Each adjusting screw 75 is threaded within a collar 76 which extends outwardly from the side plate 65 of the boom. By loosening the bolts 72 and adjusting the screw 75, the lower sprocket 39 of the assembly may be moved relative to the end of the boom and after proper adjustment, the bolts 72 are again tightened. The endless chain B passes over the sprocket 39 and by providing the adjustment of the lower sprocket, said chain may be kept taut at all times.

The buckets C are mounted on the chain B and each link 77 of the chain is formed with an outwardly directed flange 78 (Figure 6) to which the bucket is welded or otherwise secured; as is clearly shown in Figure 8, each bucket has its forward end secured to the flange whereby the fulcrum or point of swinging as the bucket travels around the sprockets is toward the forward or leading end of the bucket. The rear or trailing end of the bucket is therefore caused to travel at a faster rate around the sprockets and this movement is utilized, as will be explained, to assure emptying of the buckets as they pass around the upper sprocket 39.

With the buckets secured to the chain conveyor B, said buckets travel around the boom when the conveyor is operated. The buckets move through a longitudinal chute 78a which is secured to the upper or top plate 67 of the boom and which receives any loose dirt which may be carried upwardly. A suitable guard plate 66a

(Figure 4) is secured to the bottom 66 of the boom and has a V-shaped notch 66b disposed adjacent the upper sprocket 39.

Each digging bucket comprises spaced side walls 79, a bottom 80 and a rear closed end 80a. The forward or leading end of the bottom 80 of each bucket is welded or otherwise secured to the flange 78 of the conveyor chain B. A digging blade 81 spans the open top of the bucket and is provided with digging teeth 82 which are directed forwardly of the blade. In addition certain of the buckets C are each provided with flared digging teeth 83 located at each side thereof and the number of buckets provided with the side teeth 83 is optional. It has been found that satisfactory operation may be obtained by providing the side teeth 83 on every third bucket but the invention is not to be limited to this arrangement since if desired, every bucket may have said side teeth.

In operation of the boom and bucket assembly A, the assembly is disposed forwardly and downwardly with respect to the forward movement of the machine and the chain B which has the buckets attached thereto travels in the direction 25 of the arrow in Figure 1. As each digging bucket engages the earth, its digging blades which include the forwardly directed digging teeth 82 remove the earth which is directed rearwardly within said bucket. Actually, the buckets tunnel under or rip out the earth and it is this action which applies a downward force to the boom assembly into the machine, whereby the rear portion of said machine is maintained in engagement with the ground no matter how hard the digging may be. A major portion of the digging is done as the buckets move upwardly from point D to point D' in Figure 1 and as the earth is removed, it falls into the buckets. This arrangement prevents packing of the dirt in the buckets, 30 particularly when operating in soft and sticky earth.

At the same time that the forward teeth 82 of the digging blades are removing the earth, the flared side teeth 83 on the side wall 79 of certain 45 of the buckets shave off chips of earth, which chips fall loosely to the bottom of the bucket. This means that the sides of the ditch are actually sheared or shaved by the flared side teeth 83 and assures that the walls of the ditch will be 50 substantially smooth.

As each bucket performs its digging operation, it moves upwardly along the boom and the dirt which has been removed therefrom and has fallen or passed into the said buckets is carried 55 to the top of the boom assembly. As the receiving buckets pass over the upper sprocket 39, the particular mounting of each bucket nearer its forward end develops a considerable centrifugal force at the rear or trailing end of the bucket. 60 Obviously, the rear end of each bucket will be "flipped" or given a sudden rapid turning motion around the upper sprocket to assure efficient and complete discharge of the contents of said bucket. The dirt is discharged into the hood 52 and is deposited upon the belt conveyor 56. This conveyor, as has been explained, carries the dirt to one side of the machine and deposits the same in a row behind said machine. After the digging 65 operation is complete, the winch or drum 47 is actuated to lift the boom assembly A upwardly by means of the lifting cable 46, and this upward movement draws the boom into a position between the side members 11 and 12 of the frame 70. The assembly A is raised a sufficient distance

so that it is wholly within the frame so that the machine may be readily moved to other locations.

From the foregoing, it will be seen that a simple compact device for digging ditches is provided. Because of a particular digging action and disposition of the boom, the machine may be made relatively light in weight, since the weight of the machine is not depended upon to maintain the rear end thereof intimate with the ground. Being light in weight and relatively small in size, the machine is extremely mobile, and is also adaptable for use in small areas or spaces and in places where low overhead clearance is had. Because of its small compact size, it is capable of operating with extremely sharp turns or turns of small radius. The adjustability of the rear wheel mountings make the machine exceptionally practical in operating on inclined terrain or slopes while still maintaining the frame and the ditch formed thereby truly vertical. All of the parts of the machine are operated from the single engine 33 through the various transmissions and drive connections as illustrated in Figure 2, which arrangement increases the simplicity. It is noted that the various drive connections to the operating elements include suitable clutches which are shown in the drawings but which have not been described because such clutches are usual in this type of drive mechanism. An important feature of the invention is the arrangement of the digging buckets which, as explained, prevents the packing of dirt therein; also, the mounting of the buckets on the chain allows the centrifugal force, which is developed in each bucket travelling around the sprocket, to be utilized in assuring emptying of said bucket.

The foregoing description of the invention is explanatory thereof and various changes in the size, shape and materials, as well as in the details of the illustrated construction may be made, within the scope of the appended claims, without departing from the spirit of the invention.

Having described the invention, we claim:

1. A ditch digging machine comprising, a substantially rectangular frame having an upper horizontal end, a lower horizontal end, a vertical rear end, and a vertical forward end, said vertical rear end including a pair of vertical members spaced horizontally with respect to each other, said upper horizontal end including a pair of horizontal members spaced horizontally with re-

spect to each other, said lower horizontal end including a pair of horizontal members spaced horizontally with respect to each other to leave an open unobstructed space therebetween, a horizontal pivot rod connected to and extending between said vertical members, an elongate digging boom having its upper end pivotally connected to said horizontal pivot rod for vertical swinging movement from a digging position extending downwardly below said lower horizontal members to a retracted position above said lower horizontal members but below said upper end of said frame and within the confines of said forward end and said rear end of said frame, a wheel support on each side of said frame extending between and connected to the upper and lower ends of said frame, a stub axle mounted on each wheel support and extending horizontally therefrom so that said frame is open and free from obstruction below its upper end for enabling said boom to be pivotally moved into said retracted position, and a wheel on each stub axle to support said frame and maintain the lower end thereof above the ground.

2. The structure set forth in claim 1, including means for swinging said boom about said pivot rod from its lowered digging position to its raised retracted position.

ALMUS H. GARDNER.
CHARLES W. PEWTHERS.
